UNITED STATES PATENT OFFICE

HERON L. HEDGPETH, OF OAKLAND, CALIFORNIA, ASSIGNOR OF ONE-HALF TO
NELSON M. BARNHART, OF OAKLAND, CALIFORNIA

ADJUSTABLE SUPPORT FOR PORTABLE POWER SAWS

Continuation in part of application Serial No. 244,411 filed January 3, 1928, now patent No. 1,756,121. This application filed May 22, 1928. Serial No. 279,703.

This invention relates to supports, and particularly to a support that can be used in connection with power driven portable saws.

This application is a continuation in part of my prior application, Serial No. 244,411, filed January 3, 1928, Patent No. 1,756,121.

Small power driven circular saws are now in quite general use. Such saws are ordinarily equipped with a direct connected electric motor, and a handle provided with a trigger for controlling the circuit of the motor. In order to use such saws, they must be supported in the hand; and it is obvious that due to the weight of such apparatus, as well as to the fact that the work must also be held in proper position with respect to the saw, the manipulation of such saws is by no means simple. It is accordingly one of the objects of my invention to make it possible to utilize such saws in a more convenient manner.

With the aid of my invention, a portable power driven saw can be converted in a simple and inexpensive manner, to provide a device that is similar to a power driven table saw; yet my frame for accomplishing this result can be very easily transported and set up at any desired location. It is accordingly another object of my invention to provide a saw supporting frame that can be readily clamped or otherwise fastened to a bench or table, and that will guide accurately the relative movement of the saw and the work.

It is still another object of my invention to provide a simple, inexpensive frame by the aid of which the depth or angle of the cut can be readily adjusted; as well as to make it possible to incline the plane of the cut at any desired angle.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a lim-

iting sense, since the scope of my invention is best defined by the appended claims.

Referring to the drawings:

Figure 1 is a side view partly in section, of one form of my invention shown as applied to a portable circular power driven saw;

Fig. 2 is a plan view of the same;

Fig. 3 is a perspective view thereof, showing how the saw can be tilted to produce a slanting cut;

Fig. 4 is a fragmentary elevation showing how the saw can be supported in a position at right angles to that shown in Fig. 1; and

Fig. 5 is a detail sectional view, taken along plane 5-5 of Fig. 4.

In the present instance, I show a circular saw device arranged to be driven by an electric motor 11, that is supported on the frame forming my invention. The saw is shown at 12; it can be connected by appropriate gearing with the motor 11. The saw mechanism itself, forming no part of the present invention, need not be described, except to state that a handle or grip 13 is provided for guiding it manually, and that a trigger 14 on the handle serves to control the motor 11. Electric power is furnished through flexible leads 15. A base plate 16 is also shown, on which the motor and saw are fastened.

A work bench 17 is used upon which the material, such as lumber, to be sawed is accommodated. To this bench or table is fastened the supporting frame, by the aid of which the saw mechanism 11-12 is supported above the table.

For this purpose, I show in the present instance a clamp 18, having a pair of horizontal, spaced jaws 19 and 20. Between these jaws extends one edge of bench 17, as clearly shown in Fig. 1, and the jaws are clamped thereto by the aid of a clamping screw 21 that is threaded for example in the lower jaw 20 and has a flat portion 22 for engaging the lower surface of table 11.

Formed in this instance integrally with the clamp 18, is a split tubular socket member 23 having a vertical axis. The two parts of the socket member each have extensions 24 for accommodating a clamping

screw 25 that springs the two parts together for clamping a standard 26 therein.

This standard 26 serves as the main support for the saw mechanism. For this purpose, it has a heavier portion 27 that in turn supports a horizontal guiding arm 28. Before proceeding with the details of the guide, the features of construction of the standard 26-27 will be described.

10. This standard is so arranged that it has two adjustments: one vertically in socket 23, and the other angularly about the axis of the socket. The angular adjustment is readily accomplished by loosening screw 25, and 15 rotating the standard in the socket 23 to the desired position. The vertical adjustment can be effected by moving the whole standard axially. In the present instance I show a screw arrangement for easily accomplishing this function.

Thus standard 26-27 is made hollow, and in it there is accommodated a long screw 29. This screw is threaded in a nut 30 that fits into the bore of the standard. This nut has 25 a projecting pin 31 that passes through a vertical slot 32 in standard 26, and rests on the top edge of the socket 23. It is evident that if standard 26-27 be held against rotation in the socket 23, and if nut 30 is adjusted 30 vertically in the standard, the vertical position of the standard will be correspondingly adjusted. The screw 29 is used for the vertical adjustment of the nut. In order to ensure that the screw 29 will be maintained 35 against axial movement with respect to standard 26-27, any desired device can be used. For example, a collar 33 can be fastened to the screw, at its upper end. The upper surface of this collar contacts with the 40 lower surface of the horizontal arm 28, which is fastened to the top of standard 26-27 by a series of bolts or screws 34. To provide a good rest for arm 28, the standard 26-27 can be provided with a braced horizontal extension 35.

To raise standard 26-27, the screw 25 is first loosened; then by the aid of crank 36 attached to screw 29, this screw is rotated in a direction to unscrew it from nut 30. The 50 collar 33 rises with the screw 29 and pulls the standard up. To lower the standard, screw 29 is rotated in a reverse direction, causing collar 33 to move downward. The weight of standard 26-27 and the mechanism carried 55 thereby causes it to follow the collar 33. The limit of adjustment is apparently that represented by the length of the slot 32.

The saw mechanism 11-12 is movably supported on arm 28, so that it can be transported 60 thereon along the length of the arm. Thus for example, if it be desired to cut lumber into pieces in a transverse direction, the portable saw is grasped by handle 13 and moved back and forth on arm 28, and lumber placed 65 on bench 17 will be operated upon by the saw.

By proper adjustment of the height of standard 26-27 as well as its angular position, such lumber can obviously be cut either entirely or partly through, and either straight across or on any desired bias.

The guide carriage that is movably supported on arm 28 includes a two part device 37-38. The arm 28, as shown most clearly in Fig. 5, has a wedge-shaped cross section; and parts 37-38 are formed to provide a 75 complementary wedge shaped groove. These two parts are bolted together as shown, by the aid of bolts 39. The lower part 38 has a depending lip 40 that cooperates with a stop 41 fastened to standard 26-27 for limiting 80 the inward movement of the apparatus toward the standard.

The lower part also carries a boss 42 to which is clamped a cross piece 43. This piece carries the saw mechanism. It is so arranged 85 that it can occupy either of two positions; one, such as shown in Fig. 1, whereby the plane of saw 12 is parallel to the axis of arm 28; and another, as shown in Fig. 5, whereby the plane of the saw 12 is at right angles to the axis of arm 28. The two parts 42 and 43 can be dovetailed together in either position; and for this purpose, the lower face of boss 42 can be provided with a pair of square ribs 44 and 45 intersecting at right angles, arranged to dovetail into corresponding recesses in the plate 43. It is evident that the plate 43 supporting the saw structure 11-12 can be turned at right angles to boss 42 to provide an assembly such as shown in Fig. 4. 100 Under such circumstances, the lumber or other material can be sawed by passing it in a direction parallel to the bench 17.

To hold the saw structure in position, I can use a thumb screw 46 engaging the top of bar 105 28 and threaded through guide member 37.

In order to facilitate setting the saw structure to any desired position, I prefer to provide graduations 47 on bar 28; as well as angular graduations 48¹ on the top surface of 110 socket 23, for cooperating with pin 31.

In some cases, it is desired to cut the material with a slanting or inclined cut; that is, a cut, the plane of which departs from the vertical. In order to accomplish this with 115 the aid of my device, I provide a segment support 48 that directly carries the saw structure, being fastened thereto as by bolts such as 49. This segment has an arc shaped flange 52 that is grooved longitudinally at 50 to permit angular adjustment of the segment with respect to block 43. The lower surface of block 43 is curved to fit the arc of this flange. A bolt 51 or other fastening means passes through slot 50 as well as through block 43 125 to hold the segment 48 and block 43, to the plate 38.

It is to be noted that the axis of the flange 52 is at an angle (preferably at a right angle) 130 with respect to the axis of saw 12, whereby

the adjustment of the flange with respect to block 43 provides a displacement of the saw from a vertical axis. Such displacement is shown in Fig. 3. In this way, an inclined cut can be produced by the saw.

5 The details of the structure have now been completely described. A summary of its operation can now be set forth.

After the clamp 18 is in place on the table 10 or bench 17, the standard 23-27 can be slipped into socket 23. The pin 31 will rest on the top surface of the socket. The vertical position of the standard can be adjusted by proper manipulation of handle 36, whereby 15 the depth of the saw cut is determined. After this adjustment, the socket 23 is tightened around standard 26 by the aid of clamp screw 25. Before such tightening, the angularity of the arm 28 with respect to bench 17 can 20 also be adjusted by rotating the standard 26 in the socket 23 so as to position pin 31 directly over the appropriate graduation 48.

The carriage 37-38 can now be moved along arm 28 to guide the saw transversely 25 of the table 17; or else if desired, the saw structure can be held in position on arm 28 by screw 46, and the material to be sawed can be passed to the saw. This latter mode of operation is used when the saw 12 is parallel to the table 17, as shown in Fig. 4. In 30 case inclined saw cuts are needed, the segment 48 can be angularly adjusted with respect to block 43. This is accomplished by first loosening bolt 51 and then tightening 35 it after the adjustment is secured.

It is to be noted that the saw structure 11-12 is supported at a considerable distance below arm 28, whereby the weight 40 thereof lends substantial stability to the entire device; furthermore, the entire saw can be easily removed from the frame by merely unfastening screw 51, and the saw can then be used as an ordinary portable saw.

I claim:

45 1. In a supporting frame for a portable motor driven saw, means forming an arm, a carriage movable along and supported upon said arm said carriage having an exposed arcuate bearing surface, a member adjustable 50 on said carriage, said member being in the form of a segment having a slot in its periphery and having a curvature corresponding to the curvature of the carriage thereby permitting angular adjustment of the saw, and fastening means passing through said slot for holding said member to said carriage.

2. In a supporting frame for a portable power driven saw, a vertically adjustable standard, a horizontal arm carried by said 60 standard, a carriage movable along and supported upon said arm said carriage having an exposed arcuate bearing surface, a member adjustable on said carriage, said member being in the form of a segment having 65 a slot in its periphery and having a curva-

ture corresponding to the curvature of the carriage thereby permitting angular adjustment of the saw, and fastening means passing through said slot for holding said member to said carriage.

70 In testimony whereof I have hereunto set my hand.
